ROTATABLE DERRICK

Ola L. Berby and Robert P. Fox, Duluth, Minn., assignors to Clyde Iron Works, Inc., Duluth, Minn., a corporation of Minnesota

Application April 22, 1943, Serial No. 484,086

16 Claims.

(Cl. 212—59)

Our invention relates to an improvement in rotatable derricks wherein it is desired to provide a novel type of derrick particularly adapted to be mounted on the deck of a boat.

It has become necessary or desirable to provide a derrick which may be rotatably mounted on a supporting platform and which may be moved longitudinally upon the deck of a boat so that the boat may be unloaded without the use of a derrick mounted upon the shore. This derrick is particularly useful in the transferring of cargo from one boat to another and for unloading the boat where dock facilities are not available.

Several difficulties prevent the use of the usual type of rotatable derrick or "Whirley" upon the deck of a boat. In the first place the A-frame structure of such derricks usually projects considerably above the top of the operating cab, thereby interfering with proper vision from the wheel house of the boat. Furthermore this erect A-frame structure raises the center of gravity of the derrick, making the same more difficult to hold stationary in rough weather. Furthermore the boom of such derricks is ordinarily pivoted to the base of the hoisting mechanism platform which makes it difficult for the derrick to lift a load to the dock or boat at a considerably higher level than the deck of the boat on which the derrick is mounted.

It is the object of the present invention to provide a rotatable derrick with a suitable A-frame projecting above the top of the hoisting mechanism compartment and to pivotally secure this A-frame so that it may be folded down when not in use. As a result the A-frame, when in erected position, can properly support the boom, while at the same time when not in use the A-frame may be folded down to prevent obstruction of vision and also to lower the center of gravity of the derrick.

A feature of the present invention lies in the provision of a pivotally mounted A-frame which is secured to the boom by means of a fixed flexible connection and to provide a suitable line for erecting the A-frame into elevated position. Thus the boom may be raised and lowered by pivoting the A-frame while the angle between the A-frame and the boom remains constant. In other words in the preferred construction of our derrick no peaking cable is provided between the A-frame and the boom, but in place of such a peaking cable a line of fixed length is connected to the A-frame so that the A-frame may be raised and lowered with the boom.

A further feature of the present invention re-

sides in the provision of a novel means of regulating the movement of the derrick along the deck of the boat. While loading or unloading cargo the change in the load distribution will likely cause a fore and aft tilt of the boat with danger of the derrick slipping on its supporting track. To eliminate this danger we provide a rack engaged by a suitable driving sprocket by means of which the derrick may be moved longitudinally along the deck. By means of this rack and pinion arrangement, the derrick may be mounted in any set position longitudinally of its supporting track.

A further feature of the present invention resides in the construction of the turn-table upon which the cab or hoisting mechanism platform of the derrick is mounted. The cross section of the track circle is a channel shape with the upper and lower flanges machined on a taper to engage the tapered rollers supporting the hoisting mechanism. The track circle being securely fastened to the base is therefore able to resist both upward and downward loads transmitted from the track rollers. This feature provides stability for the loaded derrick without the use of counterbalance which is important since it reduces the overall weight of the derrick and permits carrying that much additional cargo.

A further feature of the present invention resides in the provision of a sliding cupola upon the top of the cab which permits the hoisting line to move in a straight path toward the hoisting drum. It will be understood that as the cable is wound upon the hoisting drum, the cable line moves transversely to some extent with respect to the drum as it is wound upon the drum. Therefore an elongated opening would ordinarily be required in the roof of the cab through which the hoisting line must pass in order to permit the cable to be properly wound upon its drum.

In order to compensate for this lateral movement of the cable during the hoisting operation, we provide a fleeting sheave mounted upon a hanger frame supported above the cab roof. This fleeting sheave is free to move laterally upon its supporting shaft. An elongated opening is provided in the cab roof through which the hoisting cable may pass. A cupola is secured to the sheave for lateral movement therewith, and this cupola covers the elongated opening through the cab roof. The cupola is substantially wider than the elongated opening so that the opening through the cab roof is at all times covered by the cupola regardless of the angularity of the hoisting cable.

In preferred form a flange or frame encircles the

elongated opening in the cab roof and projects upwardly from the roof into overlapping relation with the walls of the cupola. As a result most of the moisture or water which would otherwise enter the cab through the hoisting line opening therein is prevented from entering the cab.

A further feature of the present invention lies in the mounting of the boom to the top of the derrick cab, rather than to the bottom of the same, as is usual practice. With this construction the base of the boom is elevated sufficiently to allow the boom to swing free of an adjoining ship's rail or other obstacles while suspending the load at the proper operating radius.

A further feature of the present invention resides in the provision of a swivel supporting the boom point sheave. This swivel allows the boom point sheave and block hanger to align themselves with the load when the boom is tilted due to the list of the boat. This feature eliminates transverse stresses in the block hanger and eliminates torsional stresses in the boom.

These and other objects and novel features of our invention will be more clearly and fully set forth in the following specification and claims.

In the drawings forming a part of our specification:

Figure 1 is a diagrammatic elevational view showing our derrick in operation.

Figure 2 is a side elevational view of our derrick showing in full lines the boom erected and showing in dotted outline the boom in lowered position.

Figure 3 is a top plan view of the derrick illustrated in Figure 1.

Figure 4 is a diagrammatic front elevational view of the derrick with the boom, A-frame, and hanger frames removed therefrom.

Figure 5 is a sectional view through one of the derrick trucks showing the manner in which the truck is attached to the supporting rail and showing the manner in which the truck is propelled.

Figure 6 is a side elevational view of one of the derrick supporting trucks, a portion of the driving gear having been broken away to show the construction thereof.

Figure 7 is a top plan view of the boom point showing the swivel support for the boom point sheave.

Figure 8 is a sectional view of the boom point, the position of the section being illustrated by the line 8-8 of Figure 7.

Figure 9 is a front elevational view of a slideable cupola mounted over the cab roof.

Figure 10 is a sectional view through the operating cupola shown in Figure 9.

Figure 11 is a sectional view taken on a vertical plane through the carriage supporting the hoisting mechanism frame upon its circular track.

Figure 12 is a top plan view of the carriage illustrated in Figure 11.

Figure 13 is a perspective view of the boom connection with the cab of the derrick.

The derrick A is in preferred form mounted upon a pair of spaced rails 10 secured to the surface 11 of the deck of a boat or the like. As best seen in Figures 1 and 4 of the drawings, the derrick is preferably mounted upon the raised portion 11 of the deck, the edge portions 12 thereof providing walks on either side of the derrick between the derrick and the side rails 13 of the boat B.

The derrick A is mounted upon two pairs of

spaced trucks C which are mounted for motion longitudinally of the tracks 10. The trucks C support a substantially rectangular frame 14 upon which the rail circle 15 is mounted. A central rotatable connection 16 acts to connect the frame 14 with the hoisting mechanism frame, platform, and cab illustrated in general by the letter D. The platform and cab D are rotatably supported upon equalized carriages 17, 18, 19 and 20, the positions of which are indicated in Figure 3 of the drawings. In preferred form the carriages 17 and 18 are located on opposite sides of the platform and cab D near the rear end thereof, while the other equalized carriages 19 and 20 are located on either side of the center near the front of the cab and platform D.

An upright supporting frame 21 extends upwardly near the front end of the platform D to act as a support for the boom 22, the A-frame 23, and one end of the hanger frames 24. As illustrative of a manner in which this connection may be formed the top of the frame 21 is illustrated in Figure 13 of the drawings as including an upright bracket 25 arranged on a substantially vertical plane to which the bifurcated end 26 of the boom 22 is connected. The end 26 or one side of the boom 22 is connected to the bracket 25 by means of a suitable pivot device 27. The opposite side of the boom is similarly connected to the other side of the frame 21. The bracket 25 is also provided with a suitable pivot hole 28 by means of which the supporting standard 21 may be connected to the forward end of a hanger frame 24.

A pair of oppositely disposed substantially triangular plates 30 are welded or otherwise affixed to the end 26 of the boom 22, and these plates 30 are provided with aligned pivot openings 31 to accommodate a pivot 32 connecting the boom with one side of the A-frame 23. As will be noted in Figure 3 of the drawings, the A-frame is substantially A-shaped in formation, and opposite ends of the base of the A are pivotally connected to the plates 30.

A supporting bracket 33 is mounted upon the A-frame 23 and is rigidly attached thereto in any suitable manner. This bracket 33 is engageable with the upper surface of the boom in lowered position of the A-frame, as will be later described in detail. A hoisting line sheave 34 is supported by the A-frame 23 to guide the hoist line or cable 35 to the sheave 36 on the boom point 37. The line 35 extends through a suitable pair of blocks 39 and 40 and is dead-ended to one of blocks, such as to the block 40. The block 39 is supported by a hanger 41 to the boom point, while the block 40 is provided with a hook 42 or other suitable implement.

A block 43 is mounted at the apex of the A-frame 23 and a hanger line 44 extends between the block 43 and a cooperable block 45 in the frame 24, the forward end of which is pin connected to the brackets 25 by pivots 46. The rear end of the hanger frame 24 is pin connected at 47 to vertically extending frame 49 which is pin connected at 50 to the hoist mechanism platform 51.

The hanger line 44 extends between the blocks 43 and 45 and passes over the sheave 52 to the boom hoist 53 mounted upon the hoisting mechanism platform 51 within the cab 54. The hoist line 35 extends over the sheave 34 on the A-frame 23 and passes over the fleeting sheave 55 mounted between the hanger frames 24 and the roof of the cab 54 extending downwardly into

the cab to the load hoist 56. Provided within the cab 54 is a swinger unit 57 by means of which the hoist may be rotated to any desired position. This swinger unit operates a shaft 59 supporting a pinion 60 which causes rotation of the gear 61. The gear 61 is mounted upon the shaft 62 of a pinion 63 which engages teeth on the rail circle to rotate the platform and cab D in either direction. Obviously by operation of the swinger 57 the gear may be operated to rotate the pinion 63 which acts to engage the rail circle and to rotate the cab.

The supporting trucks C are constructed as best illustrated in Figures 5 and 6 of the drawings. The trucks are positioned beneath the corners 64 of the frame 14. Each corner 64 is connected through the equalizer support 65 to the equalizer shaft or pin 66. A pair of side plates 67 forming a part of the truck are centrally supported upon the equalizer shaft 66. The equalized trucks are provided with spaced transversely extending shafts 69. The supporting wheels 70 are supported upon the shafts 69 and ride upon the rails 10.

In order to prevent the truck from raising from the rails when a tendency is provided for the derrick to tilt, we provide a transverse shaft 71 extending through a depending lug on each truck 67 to support a depending casting 72. This casting 72 extends down into close proximity with the head of the rail 10 and a pair of opposed hook-shaped flanges 73 extend down beneath the head of the rail to grip the head in case a tendency for the truck seat to raise from the rail is provided.

Mounted upon the shaft 66 we provide a gear 74 which is provided with a hub 75 encircling the shaft 66 and held in place by a bolt 76 or any other suitable means. The gear 74 includes a series of gear teeth 77 and a second set of sprocket teeth 79 in laterally spaced relation thereto. The gear teeth 77 are designed for engagement with the pinion 80 mounted upon a transverse shaft 81 which also supports a gear 78. The gear teeth 79 are designed to engage between spaced rollers 82 mounted upon bolts or rivets 83 extending between two spaced strips 84 mounted on edges adjacent the deck surface 11. The two upright strips 84 with their connecting bolts 83 form a rack for engagement with the teeth 79 of the gear 74.

A motor 85 is mounted upon the frame 14 and this motor is gear connected to a shaft 86. A pinion 88 on the shaft 86 drives the gear 78 on the shaft 81. The pinion 80 on the shaft 81 drives the gear 77, also driving the sprocket teeth 79 and moving the derrick along the deck.

As the hoist line is wound upon the drum of the load hoist 56 the line will move from one end to the other of this drum. As the line passes through the roof of the cab it is desirable to have some sort of shield for the elongated opening through which the cable must pass to prevent water from entering the cab 54.

In order to accomplish this result we use the structure best illustrated in Figures 9 and 10 of the drawings. The hanger frames 24 are provided with a pair of downwardly extending plates 87 between which extend a shaft 89 upon which is supported the fleeting sheave 55. Mounted on either side of the sheave 55 and depending downwardly from the shaft 89, we provide a pair of plates 90 which are spaced from the sheave 55 by suitable spacing means 91. A cupola 92 is supported by the plates 90, this cupola compris-

ing a curved upper surface 93 designed to fit about the sheave 55, an inclined plate 94 forming the back of the cupola, a flat plate 95 secured to the lower extremities of the plates 93 and 94, and a skirt 96 depending from the plate 95. The hoist line or cable 35 extends through a sleeve 97 between the plates 93 and 94 and through an opening 98 in the plate 95. The spacing means 91 are guided by the fleeting sheave and cause the cupola 92 to fleet with the sheave.

An opening 100 in the cab roof is elongated sufficiently to take care of the angularity of the line 35 passing to the drum of the load hoist 56. A frame 101 projects upwardly from the cab roof 102 encircling the opening 100. The frame 101 is shown as formed of channel iron with the base of the channel inwardly and flush with the sides of the opening 100, while the sides of the channel extend on parallel horizontal planes. In operation the cupola is of substantially larger size than the frame 101 so as to permit the necessary lateral movement or fleeting of the cupola 92 with the sheave 55. As the skirt 96 extends downwardly into overlapping relation with the frame 101, little water can enter the cab. At the same time free movement of the cable through the roof is permitted.

In Figures 11 and 12 of the drawings we disclose one of the equalized trucks for supporting the mechanism platform and cab D. As each of the trucks 17, 18, 19 and 20 are identical in form the carriage illustrated is designated as the carriage 17, it being understood that the carriages 18, 19 and 20 are of similar formation.

A plate 103 extends beneath the frame 51 of the hoisting mechanism platform and a pair of arms 104 and 105 extend downwardly from the plate 103. The ends of the arms 104 and 105 encircle a shaft 106 which is supported by a carriage body 107.

The carriage body 107 is provided with a pair of laterally extending wings or flanges 109 and a second pair of parallel laterally extending flanges 110. Roller axles 111 extend through the wings 109 and 110. The axis of each roller axle 111 extends radially from the center of curvature of the rail circle 15. The ends of the roller axles 111 support rollers 112.

The rail circle 15 has teeth 116 on its outer surface to cooperate with the pinion 63 in rotating the platform and cab D. The rail circle 15 is substantially channel-shaped in cross-section having a laterally extending upper flange 117 and a laterally extending lower flange 119 upon which the rollers 112 operate. The flange 117 prevents raising of the roller 112 while the weight of the derrick is normally supported by the flange 119.

It will be noted that when the derrick is in use the A-frame 23 is elevated by the boom, raising the hanger line 44, and elevations of the boom are adjusted by means of this hanger line 44. A cable 120 connects the apex of the A-frame 23 with the boom point 37 so that the A-frame and the boom pivot in unison until it is desired to lower the A-frame. The hoist line 35 may be operated to lift the load and the hoisting mechanism platform and cab D may be pivoted to any desired position.

When the derrick is not in use tie rods such as 121 may be provided to secure the platform 51 to the frame 14. The A-frame 23 is pivoted by releasing the tension on the hanger line 44 until the boom 22 is in the lowered position illustrated

in dotted outline in Figure 2 of the drawings. At this point of the rotation the A-frame 23 is positioned forwardly of the vertical position so that by further controlled release of the hanger line 44 the A-frame 23 may be lowered until the bracket 33 rests upon the upper surface of the boom 22.

The bracket 33 is provided so that the hanger line 44 may still be operated to raise the A-frame. Obviously if the A-frame 23 pivoted to too great an extent the hanger line 44 would drop below the shaft 32 and the hanger line could not operate to lift the A-frame. When the boom 22 is in lowered position it may be secured to the deck by suitable anchors such as 122, thus preventing any movement of the boom with respect to the deck.

The sheave 36 is mounted upon a shaft 123 which is supported between parallel sides 124 of a swivel frame 125. The frame 125 is provided with a pair of aligned pivots 126 having their axes extending longitudinally of the boom 22. These pivots are mounted in the cross members 127 and 129 of the boom point 37. Thus if the load supported by the sheave 36 swings to one side or to the other of a vertical plane, the sheave swivels with its frame so that the axis of the sheave remains at right angles to the plane of the load line depending from the sheave.

The novel boom mounting makes it possible to maintain a low center of gravity, and at the same time to use the derrick for transferring heavy materials to or from a level substantially above the deck level of the boat on which the derrick is mounted. The relative position of two boats B and E is shown in Figure 1, this figure diagrammatically showing the advantage of the derrick construction. It will be noted that the deck of the boat E is well above the top of the derrick cab D of the derrick A on the boat B.

In accordance with the patent statutes, we have described the principles of construction and operation of our derrick, and while we have endeavored to set forth the best embodiments thereof, we desire to have it understood that obvious changes may be made within the scope of the following claims without departing from the spirit of our invention.

We claim:

1. A derrick comprising a rotatable platform, a boom pivotally secured to said platform, an A-frame pivotally secured to said platform, a flexible connector of fixed length connecting the apex of said A-frame and the point of the boom, and means for pivoting said A-frame and boom in unison, the length of said connector being such that when said boom is pivoted slightly above horizontal position, said A-frame is inclined beyond vertical position.

2. A derrick comprising a platform, a boom pivotally secured to said platform, a frame pivotally secured to said platform adjacent said boom, means connecting the free end of said frame to said boom at a point spaced from said pivotal connection between the boom and said platform, and means for pivoting said frame and boom in unison, the length of said connecting means being such that when the boom is pivoted slightly above horizontal position, said A-frame is inclined beyond vertical position.

3. A derrick comprising a rotatable platform, a boom pivotally secured to said platform, a frame element pivotally secured at one end to said boom, means connecting the free end of said frame and said boom at a point spaced from the

pivotal connection between said boom and said platform, and means for raising and lowering said boom and said frame in unison, the length of said connecting means being such that when the boom is pivoted slightly above horizontal position, said A-frame is inclined beyond vertical position.

4. A derrick comprising a rotatable platform, a boom pivotally secured to said platform, a frame pivoted to said platform adjacent said boom, a flexible connecting means connecting the free end of said frame with said boom at a point substantially spaced from the pivotal connection between said boom and said platform, means for pivoting said boom and said frame in unison, said frame being pivoted against said boom when said derrick is not in use, the length of said connecting means being such that when the boom is pivoted slightly above horizontal position, said A-frame is inclined beyond vertical position.

5. A derrick comprising a rotatable platform, a boom pivotally secured to said platform, an A-frame pivotally secured to said platform adjacent said boom connection, a flexible connecting means connecting the apex of said A-frame with the point of the boom, a bracket on said A-frame, said A-frame being foldable with respect to said boom so that said bracket rests against said boom.

6. A derrick comprising a rotatable platform, a boom pivotally secured to said platform, a frame pivotally secured to said platform adjacent said boom, hanger frame means connected to said platform adjacent said boom and connected at its opposite end to said platform, flexible means connecting said frame and said boom to hold said frame and said boom in a predetermined angular relationship during operation of the boom, said hanger frame means and said frame supporting suitable block means, and a hanger line extending from said block means by means of which said boom may be raised and lowered.

7. A derrick including a rotatable platform, a cab mounted upon said platform, a frame on one side of said platform adjacent one end of said cab extending above the level of the cab, a boom pivotally secured to said frame, an A-frame pivotally secured to said frame, hanger frame means connected at one end to said frame and at its other end to said platform, cooperable blocks on said hanger frame means and said A-frame, a line extending through said blocks by means of which said A-frame may be raised and lowered, and a flexible connection between said A-frame and said boom to hold said boom and A-frame in fixed relation while the boom is in operation.

8. A derrick comprising a supporting frame, a track circle mounted upon said frame, a series of equalized carriages mounted on said rail circle, a rotatable cab and platform supported by said equalizer carriages, each of said carriages including roller means, and said rail circle being channel-shaped in cross section with one side of the channel extending over the roller means and the other side of the channel extending beneath the roller means, said roller means and cooperating channel sides tapering larger toward the base of the channel.

9. A rotatable platform mounting including a rail circle channel-shaped in cross section with the sides of the channel superimposed one above the other, and a series of equalized carriages, each carriage including a roller engageable between the flanges of said rail circle, each roller tapering toward the point at the center of the circle,

and a shaft on each roller supporting the body of the carriage.

10. A rotatable derrick platform support comprising a supporting frame, a rail circle being channel-shaped in cross section and including inwardly extending side flanges in superimposed relationship, a carriage bracket extending downwardly from the platform, a pair of radially extending shafts supported by said bracket in spaced relationship, and a pair of rollers on said shafts extending between the flanges of said rail circle, said rollers being tapered toward a point at the center of the circle.

11. A rotatable platform support for a derrick comprising a supporting frame, a rail circle mounted upon said frame, said rail circle being channel-shaped in cross section with two inwardly extending superimposed flanges, a bracket extending downwardly from the platform, an equalizing body centrally pivoted to said bracket, a pair of radially extending shafts oppositely disposed on either side of said bracket supported by said body, and rollers on said shafts engaged between the flanges of said rail circle, said rollers being tapered toward a point at the center of the circle.

12. A ship derrick designed for use upon the deck of a ship or the like, comprising a pair of rails mounted in parallel relationship longitudinally of the deck, a frame supported upon said rails, cooperable means on said frame and said deck to prevent slipping of said frame along said rails, a platform rotatably mounted upon said frame, a boom pivotally secured to said platform, and an upwardly extending A-frame on said platform pivotally secured to said platform to pivot down against said boom when not in use.

13. A ship derrick designed to be mounted upon the deck of a ship comprising a pair of longitudinally extending lines on the deck of the ship, a frame mounted on said lines for longitudinal movement thereupon, a platform rotatably mounted upon said frame, a derrick mounted

upon said platform, a rack on said deck extending longitudinally thereof and parallel to said rails, and gear means on said frame engageable with said rack, said gear means being operable upon rotation to move said frame, platform, and derrick longitudinally of said deck.

14. In combination with a derrick having a platform, a boom pivotally secured thereto, a frame extending upwardly from said platform, a cab on said platform, and a line extending from said frame through the roof of said cab, a cable guide comprising a transverse shaft, a sheave mounted for transverse movement along said shaft over which said line may extend, and a cupola supported by said shaft laterally slideable with said sheave, said cab roof having an opening therethrough over which said cupola extends.

15. In combination with a derrick having a hoisting mechanism platform, hoisting mechanism mounted thereon, a cab over said hoisting mechanism having a hole therethrough, and a line from said hoisting mechanism through said hole, a sheave pivotally supported above said cab roof and mounted for lateral movement with respect thereto, said sheave guiding said line extending through said hole, and a cupola laterally movable with said sheave, said cupola covering said opening in various adjusted positions of said sheave.

16. A derrick including a derrick platform, hoisting mechanism mounted thereupon, a cab over said hoisting mechanism, a cab roof having an opening therethrough, a line from said hoisting mechanism extending through said opening, a sheave laterally adjustably mounted above said cab roof to guide said line passing through said opening, an upwardly extending frame on said cab roof encircling said opening, and a cupola laterally adjustable with said sheave encircling said frame.

OLA L. BERBY.
ROBERT P. FOX.
